PIPE HANGER AND SEALING STRUCTURE
FOR WELL HEADS

Marvin R. Jones and John E. Eckel, Houston,
Tex., assignors to Petroleum Mechanical De-
velopment Corporation, Houston, Tex., a cor-
poration of Texas

Application October 20, 1950, Serial No. 191,198

7 Claims. (Cl. 285—22)

1

This invention relates to a well head assembly and particularly to a pipe hanger and sealing unit for such assembly.

A principal object of this invention is to provide in a well head an improved type of pipe hanger and seal unit which may be installed on and about the pipe after the pipe has been inserted into the well through the usual casing-head.

Another object is to provide such a unit in which the seal member is actuated by downward pull exerted thereon by load-supporting members disposed below the seal member.

A further object is to provide a pipe hanger and seal unit comprising a bowl member, pipe-engaging slips, and a sealing assembly for sealing between the pipe and the surrounding casing-head, the several elements being of segmented construction, and hinged to be closed about a pipe for movement along the pipe into place in the supporting well head.

A further object is the provision of such a unit in which the force employed to expand the sealing element is exerted through the slip bowl.

Still another object is the provision of such a unit in which the sealing assembly comprises a support ring engageable with a seat in the casinghead, a compressible resilient sealing ring disposed on the support ring, and a compression ring mounted on the sealing ring and adapted to be connected to the upper end of the slip bowl for axial movement thereby relative to the support ring in response to loads applied to the slip bowl.

An additional object is the provision of means for movably linking the slips to the slip bowl.

Other and more specific objects and advantages of this invention will become evident from the following detailed description when read in conjunction with the accompanying drawings which illustrate one useful embodiment in accordance with this invention.

In the drawings:

Fig. 1 is a longitudinal sectional view, taken generally along line 1—1 of Fig. 2, of a well head assembly in accordance with an embodiment of this invention, showing the pipe hanger and seal unit in pipe-supporting and sealing position in a well head;

Fig. 2 is a top plan view of the upper end of the pipe hanger and seal unit; and

Fig. 3 is a view in perspective of the pipe hanger and seal unit shown in open position for mounting on a well pipe before insertion into the supporting well head.

2

Referring to the drawings, there is shown a casinghead, designated generally by the numeral 10, mounted in the conventional manner on the upper end of an outer string of casing 11, such as the usual surface casing of a well. Casinghead 10 is of generally conventional form, being composed of a generally tubular body 12 having an outwardly extending annular flange 13 at its upper end adapted for attachment of various upper well head fittings in the well-known manner in completing the usual composite well head structure. The bore of body 12 has an axially straight portion 14 extending from a point somewhat below the upper end of the body to its lower end and merging at its upper end into an upwardly and outwardly tapering portion forming a tapered seat 15, which, in turn, terminates in a second axially straight portion 16 which extends to the upper end of body 12. A plurality of internally threaded openings 17 are provided in the wall of body 12 communicating with the interior of the body through straight portion 14 thereof.

A tubular casing or other well pipe 18 is shown inserted through the bore of casinghead 10 to be supported therein by the pipe supporting and sealing unit, designated generally by the numeral 19, which is adapted to be inserted in the annular space between pipe 18 and the inner wall of the casinghead.

The pipe supporting and sealing unit 19 is composed of a tubular bowl 20 the outer wall 21 of which is axially straight and dimensioned to be freely but snugly slidable in straight portion 14 of the bore of the casinghead. The bore of bowl 20 is somewhat larger in diameter than the external diameter of pipe 18 and has a downwardly and inwardly inclined surface 22. The upper end of bowl 20 is provided with an inwardly extending annular flange 23, the inner diameter of which is larger than the external diameter of pipe 18 whereby the bowl will be freely movable along and about the pipe. A plurality of arcuate pipe-gripping slips 24 are mounted in the bore of bowl 20 and are provided on their inner faces with pipe-gripping teeth 25, the rear faces of the slips being tapered, as at 26, to complement the taper of inclined surface 22 of the slip bowl. With this arrangement, it will be understood that when the toothed faces of slips 24 are engaged with the outer wall of pipe 18, the load of the pipe will produce a wedging action between the slips and the inclined surface of the slip bowl to thereby cause the slips to firmly grip and support the pipe, the slip bowl

being supported against substantial downward movement in the casinghead in the manner to be subsequently described. The slips 24 are held in place in bowl 20 by means of bolts 27, the lower ends of which screw into, or are otherwise suitably connected to, outwardly extending shoulders 29 on the rear faces of the slips and extend upwardly through apertures 28 provided in flange 23. Apertures 28 are made appreciably larger in diameter than bolts 27 to provide a loose sliding fit for the bolts, which are provided at their upper ends with enlarged heads 30 so that they will not pull through apertures 28. Thus the slips may be retained in the slip bowl by means of a relatively loose linkage which will allow some degree of movement of the slips relative to the slip bowl so as to permit the slips to adjust themselves relative to the pipe and bowl during assembly and setting of the structure. Shoulders 29 form abutments which are spaced from but engageable with the lower edges of flanges 23 to prevent the slips from being pulled upwardly out of the slip bowl.

The sealing assembly includes a metal support ring 31, the inner diameter of which is such as to provide a loose fit about pipe 18. Ring 31 has an outer surface 32 which is tapered to complement the slope of seat 15 in the bore of casinghead 10. Seat 15 thereby serves as an abutment or shoulder to engage support ring 31 and resist any substantial downward movement thereof in the bore of the casinghead. A resilient compressible sealing ring 33 is mounted on the upper end of support ring 31 and is dimensioned, in its normal uncompressed condition, to fit slidably in the annular space between the exterior of pipe 18 and straight portion 16 of the casinghead bore. A metal follower or compression ring 34 is seated on top of sealing ring 33 and is also dimensioned to be freely slidable in the annular space between pipe 18 and straight portion 16 of the casinghead bore. A plurality of angularly spaced, axially registering holes 36, 37, and 38 are provided respectively in support ring 31, sealing ring 33, and compression ring 34, through which bolts 39 extend, the lower ends of the bolts being screwed into registering threaded sockets 40 provided in the upper end of bowl 20. The upper ends of bolts 39 are provided with conventional hollow heads 41 which are adapted to seat in sockets 42 formed by counterboring the upper ends of holes 38 in compression ring 34. The diameters of the several holes 36, 37, and 38 are made somewhat larger than that of the bolts 39 whereby the latter may slide freely through the several rings in response to the axial movement of the slip bowl relative to the sealing assembly, the slip bowl being thus dependently connected to follower ring 34 by the engagement of bolt heads 41 with the edge of holes 38. The lower end of support ring 31 is provided with upwardly extending sockets 43 to receive the upper end of bolts 27 and are of sufficient depth so that the latter may move freely longitudinally therein in response to relative axial movement between slips 24 and slip bowl 20. It will be understood that sockets 43 will be angularly interspersed in support ring 31 with holes 36, so as to avoid any interference between the respective relative movements of bolts 29 and 39.

As will be seen particularly in Fig. 3 slip bowl 20, support ring 31 and compression ring 34 are split diametrically to divide these members into two complementary semi-circular segments. Slips 24 are likewise segmented in a correspond-

ing manner. Sealing ring 33 is split on only one side whereby the sealing ring will serve as a flexible hinge, indicated at 35, connecting the segments of the hanger and sealing unit at the opposite side to provide an articulated connection between the several segments which will allow the unit to be opened and closed for application to, and removal from, pipe 18. The split in sealing ring 33 is preferably offset somewhat with respect to the split between adjacent metallic members of the unit, thereby forming a tongue 44 protruding from one side of one of the adjacent metallic members of the unit and adapted to enter the space between support ring 31 and compression ring 34 in the opposing side of the other adjacent member. The split in sealing ring 33 is so positioned that tongue 44 will include one of the holes 37. With this arrangement when the unit is closed about the pipe, tongue 44 will enter the adjacent space between the support and compression rings and hole 37 in tongue 44 will be brought automatically in registration with the corresponding holes 36 and 38 in support ring 31 and compression ring 34, respectively. Thus, a bolt 39 may then be inserted through these registering holes and when screwed into its corresponding socket 40 will serve to lock together the open ends of the segments of the complete unit about the pipe. It will be understood that the pipe hanger and assembly unit may be formed from any desired number of articulated segments, and that other suitable arrangements may be employed for hinging the segments to each other and for locking the open ends together when closed about a pipe.

The adjacent side edges of adjoining slips 24 are provided with cooperating sets of tongues 45 and slots 46, which are adapted to be engaged when the segments of the unit are closed about a pipe, in order to prevent relative axial movement between the slip segments, in order to assure centering of the pipe in the hanger structure.

In operation, the above-described pipe hanger and sealing unit 19, assembled as described, will be opened as illustrated in Fig. 3, one of the bolts 39 being withdrawn, as shown, for this purpose. The opened unit is then placed about a portion of pipe 18 which extends above the upper end of casinghead 10, and closed about the pipe, after which the previously withdrawn bolt 39 will be inserted through the registering holes in compression ring 34, tongue 44 and support ring 31 and screwed into registering socket 40 in the upper end of slip bowl 20. It will be understood that pipe 18 will previously have been inserted into the well through casinghead 10, and usually through a series of conventional well head fittings such as blowout preventors and master gates (not shown) which will ordinarily be in position on top of the casinghead. At this stage pipe 18 will ordinarily be suspended in a derrick from the usual hoisting and lowering equipment. (Not shown.)

When the unit has been locked around the pipe it will be allowed to slide down the pipe into the annular space between the pipe and casinghead. As the unit enters the bore of the casinghead, slip bowl 20 will descend therein until support ring 31 engages seat 15 in the casinghead, thereby arresting further downward movement of the unit. Slips 24 will then tend to slide downwardly and inwardly along inclined surface 22 of the slip bowl and engage the exterior of pipe 18. Any downward movement of the latter rela-

tive to the casinghead, as by slackening off of the derrick line by which it is suspended, will tend to set the slips firmly in the pipe wall, thereby anchoring the pipe against further downward movement. The load of the pipe will be transferred to the slip bowl by the wedging action of the slips on inclined surface 22. At the same time, the slip bowl will tend to move downwardly in the casinghead under the load thus applied thereto. This load will, in turn, be transferred through bolts 39 to compression ring 34 which will thus be drawn downwardly toward support ring 31, which remains stationary because of its engagement with seat 15. The resulting downward movement of compression ring 34 relative to support ring 31 will compress and radially expand sealing ring 33, thereby tightly sealing the annular space between the pipe and the inner wall of the casinghead.

In the structure, above described, the slip bowl will normally be dimensioned to provide a close sliding fit in the straight portion 14 of the casinghead bore. As a result upon application of the load of the pipe, the lateral forces developed by the wedging action of the slips on the sides of the slip bowl will tend to expand the latter into strong frictional engagement with the surrounding wall of the casinghead bore, whereby a very substantial part of the load on the hanger will be supported by friction, the remainder of the load being taken on bolts 39 and support ring 31 and utilized to actuate sealing ring 33.

An important advantage resulting from the described construction is that it provides a compact structure by means of which the load will be supported near the upper end of the casinghead thereby permitting the use of much shorter casingheads than those generally in use heretofore.

The pipe hanger and sealing unit in accordance with this invention, because of its compact construction, will readily pass through the bores of the usual well head fittings, such as blow-out preventors, master gates, and the like, which will normally be mounted on the casinghead during the operation of running and setting casing. The unit may thus be installed quickly and with a minimum of disturbance to the well head structure already in place.

It will be understood that in the described structure, the sealing ring may also be expanded into sealing engagement with the pipe and the surrounding casinghead independently of the weight of the pipe suspended therein. This may be done by screwing down bolts 39 in sockets 40 of the slip bowl sufficiently to compress and expand sealing ring 33 between follower ring 34 and support ring 31 to the desired extent. Or a combination of weight applied to the slips and tightening of bolts 39 may be employed to provide the desired degree of compression of sealing ring 33.

It will be understood the various alterations and modifications may be made in the details of the illustrative embodiment within the scope of the appended claims and without departing from the spirit of the invention.

What we claim and desire to secure by Letters Patent is:

1. A pipe hanger structure for supporting a well pipe which extends axially through a tubular well head member having an internal seat, comprising, a bowl member insertible within the well head member about the pipe, the exterior of said bowl member being axially straight and dimensioned to slide freely through said seat, pipe

supporting means within the bowl member, and an annular sealing assembly insertible in the annular space between the pipe and the well head member above said bowl member, said sealing assembly comprising a support ring engageable with said seat, a follower ring disposed above said support ring, a compressible resilient sealing ring disposed between said support ring and said follower ring, and a plurality of angularly spaced connection members slidably extending through said sealing assembly dependently connecting said bowl member to said follower ring.

5 2. A structure according to claim 1, wherein said bowl member and said sealing assembly comprise articulated segments adapted to be wrapped around the pipe.

10 3. A structure according to claim 1, wherein said bowl member and said sealing assembly comprise a plurality of articulated arcuate segments having a separable connection at one point between adjacent segments.

15 4. A structure according to claim 1, wherein said bowl member and said support and follower rings comprise a plurality of arcuate segments, and said sealing ring is split only at one point between adjacent segments whereby to form articulating connection between said segments at the other junctures thereof.

20 5. A pipe hanger structure for supporting a well pipe which extends axially through a tubular well head member having an internal seat, comprising, a bowl member insertible within the well head member, the exterior of said bowl member being axially straight and dimensioned to slide freely through said seat, pipe supporting means within the bowl member, connection elements connecting said pipe supporting means for longitudinal movement relative to said bowl member, and an annular sealing member insertible in the annular space between the pipe and the well head member above said bowl member, said sealing assembly comprising, a support ring engageable with said seat, a follower ring disposed above said support ring, a compressible resilient sealing ring disposed between said support ring and said follower ring, and a plurality of angularly spaced connection members slidably extending through said sealing assembly dependently connecting said bowl member to said follower ring.

25 6. A pipe hanger structure for supporting a well pipe which extends axially through a tubular well head having an internal seat and an axially straight portion below said seat, comprising, a bowl member insertible within the well head member about the pipe, the exterior of said bowl member being axially straight and slidably in the axially straight portion of said well head member, pipe supporting means within the bowl member, and an annular sealing assembly insertible in the annular space between the pipe and the well head member above said bowl member,

30 said sealing assembly comprising a support ring engageable with said seat and separate from said bowl member, a follower ring disposed above said support ring, a compressible resilient ring disposed between said support ring and said follower ring, and a plurality of angularly spaced connection members slidably extending through said sealing assembly dependently connecting said bowl member to said follower ring.

35 7. A pipe hanger structure for supporting a well pipe which extends axially through a tubular well head member having an internal seat, comprising, a support ring engageable with said seat to limit its downward movement in said well

head member, a follower ring disposed above said support ring, a compressible resilient sealing ring disposed between said support ring and said follower ring, a plurality of angularly spaced connection members connected to said follower ring and slidably extending through said compressible ring and said support ring, and a bowl member having internal pipe supporting means slidably disposed in said well head member below said seat and connected to the lower ends of 10

said connection members for longitudinal movement therewith relative to said support ring.
